UNITED STATES PATENT OFFICE

99,353

DESIGN FOR A SHOE

James P. Kyros, Lynn, Mass.

Application March 6, 1936, Serial No. 61,511

Term of patent 3½ years

To all whom it may concern:

Be it known that I, James P. Kyros, a citizen of the United States of America and resident of the city of Lynn, county of Essex, and State of Massachusetts, have invented a new, original, and ornamental Design for a Shoe, of which the following is a specification, reference being had to the accompanying drawing, forming a part thereof.

I claim:

The ornamental design for a shoe as shown.

JAMES P. KYROS.
